UNITED STATES PATENT OFFICE.

RICHARD T. NEWTON, OF NUTLEY, NEW JERSEY.

LIFTING-JACK.

1,276,796.

Specification of Letters Patent. Patented Aug. 27, 1918.

Application filed September 20, 1915. Serial No. 51,643.

To all whom it may concern:

Be it known that I, RICHARD T. NEWTON, a citizen of the United States of America, and residing at Nutley, in the county of Essex and State of New Jersey, have invented a certain new and Improved Lifting-Jack, of which the following is a specification.

My invention relates to lifting jacks, and the object of my invention is to provide a simple, rugged and efficient jack, the pawls of which are operated by a continuous rotary motion of the operating handle, whether the jack is lifting or lowering the load.

15. In the accompanying drawings,

Figure 1 is a side elevation, partially in section, of a lifting jack in which my invention is illustratively embodied;

20. Fig. 2 is a broken front elevation of the same;

Fig. 3 is an enlarged detail showing the operation of the pawls during the lowering of the load;

25. Fig. 4 is a broken partial elevation of a modified pawl construction; and

Fig. 5 is a broken elevation of an operating tool.

Most lifting jacks are provided with a lifting pawl supplemented by a holding pawl which engages the rack while the lifting pawl is moved downward to position to engage the next rack tooth. In such constructions the lifting pawl is actuated by a cam oscillated by a lever working back and forth through an arc in well known pump handle fashion. This type of jack, which is the one almost universally employed for lifting automobiles when it is desired to remove a wheel or replace a tire, requires the operator to work in an awkward and dirty position, frequently leaning against and partially under the body of the car. Moreover, half of the pump handle motion, viz., the recovery or up-stroke, is non-working and consequently adds to the time required for the jacking operation, as well as its labor.

The present construction provides a jack in which the lifting pawls are operated by a continuous rotary drive and this drive may be accomplished manually from a convenient position to one side or back of the machine.

Referring to the drawings, and particularly to Figs. 1 to 3, the jack in which my invention is here illustratively embodied,

comprises a standard 10 with foot piece 11 and a jack bar 12 vertically guided in the standard and provided at its top with a swiveling rest or seat 13 to receive the load. A double ratchet 14 with staggered teeth is 60 formed upon or attached to one face of the bar 12 and a pair of pawls 15, 16, pass through the aperture 17 in the standard into engagement with the respective ratchets and control the vertical movement of the jack 65 bar in both directions.

These pawls are gapped at the lower ends to form bearings which rest upon the cranks 18 and 19 cut in the shaft 20, being secured in position thereon by pins 21 passed beneath the cranks between the downwardly extending legs 22, 23 of each pawl. The shaft 20 is journaled in side brackets 24, 25, projecting from standard 10, and may be squared at both ends, as at 26, or have a 75 gear 27 on one end driven by pinion 28, the spindle of which has a squared end 29 detachably engaged with the hub of a crank handle 30.

The throw of the crank shafts 18 and 19 80 is slightly greater than the length of one tooth of the ratchet 14, so that as the shaft rotates in a direction to lift the jack bar 12, the upper crank (18 in Fig. 2) carries the lifting pawl 15, while the lower crank 19 85 carries the temporarily idle pawl 16 down into position to engage its succeeding ratchet tooth. The further rotation of the shaft reverses the action, pawl 16 becoming the lifting pawl and pawl 15 then becoming idle 90 and moving down into position to engage its succeeding ratchet tooth. The engagement of the pawls 15 and 16 with the ratchet is caused in part by their overweight on the side adjacent the ratchets so that they tend 95 to fall against the latter, and in part by the effort of the spring actuated catch lever 31 upon which the legs 22 of the pawls rest during the lower portion of their travel.

This catch lever 31 may be supported in 100 any suitable fashion, e. g., on a pivot pin 32 at the outer end of a bracket arm 33 which also has a stud 34 to which one end of the catch spring 35 is attached. The free end of the catch lever is cut away to form a 105 shoulder 36 and ledge 37 extending to the end of the lever. On the rotation of the shaft 20 in a direction to lower the jack bar 12, the leg 22 of the lower pawl (16, Fig. 3) rides on the ledge 37 until the outward throw 110

of its crank 19 brings it against the shoulder 36, whereupon the further throw of the crank serves to tilt the upper end of the pawl out of engagement with its ratchet and hold it in this disengaged position until the now descending pawl 15 bears against the ledge 37 and depresses the catch lever 31 so that pawl 16 is freed from the shoulder 36 and drops into engagement with the ratchet tooth 70 next above the one previously engaged thereby. This movement is of course repeated for the other pawl in its turn on further rotation of the shaft in the same direction and the bar 12 is thus progressively lowered step by step. The arrangement of 75 the catch lever 31 is such that at the moment its shoulder 36 engages the leg 22 of the lower pawl (16, Fig. 3) the upper pawl 15 has slightly lifted the bar 12 and pawl 16 is thus freed from its ratchet tooth and may clear the same on its tilting movement as 80 the crank 19 completes its outward throw.

The rack and pawl arrangement may be variously modified to accomplish the same 25 object. Thus in Fig. 4 I have shown a single rack 38 engaged by pawls 39 and 40 of different lengths. The longer pawl 40 straddles the shorter pawl 39 and has a pair of cranks 41, 42 on the same axis but lying on opposite 30 sides of the crank 43 for the short pawl. Save for the fact that the catch lever is wider so as to engage both legs of the pawl 40, its construction and operation are the same as in the construction first described.

I prefer to operate the shaft 20 by means 35 of a long handled bit 44 (Fig. 5) provided at the end of its shank with a squared socket 45 to engage the end of the shaft. By utilizing a tool of this character, there is no 40 necessity for getting into awkward or dirty positions during the use of the jack.

A removable cover 46 may be provided to inclose the ratchet mechanism and protect it from dirt or injury. Where gears such as 45 27, 28, are used, these may also be inclosed by the cover.

Various modifications will readily occur to those skilled in the art without departing from what I claim as my invention.

50 I claim as my invention:—

1. A lifting jack comprising a jack bar, a pawl and ratchet mechanism for operating the same, said mechanism comprising a plurality of single-tooth working pawls, and a 55 rotary member moving said pawls into intermittent, successive, operative engagement with the ratchet on continued rotation of said member in one direction, the operative engagements of said pawls with the ratchet 60 slightly overlapping each other, for the purpose described.

2. A lifting jack comprising a jack bar, a pawl and ratchet mechanism for operating the same, said mechanism comprising a plurality of working pawls, a shaft continu-

ously rotatable in one direction to operate the same, spring means temporarily engaging the pawls during their downward movement to press their dogging ends into ratchet 70 engaging position.

3. A lifting jack comprising a jack bar, a pawl and ratchet mechanism for operating the same, said mechanism comprising a plurality of working pawls, a shaft continuously rotatable in one direction to operate 75 the same, spring pressed means common to all of said pawls and temporarily engaging the latter successively on their downward movement to press their dogging ends into ratchet engaging position.

4. A lifting jack comprising a jack bar, a pawl and ratchet mechanism for operating the same, said mechanism comprising a plurality of working pawls, a shaft continuously rotatable in one direction to operate 85 the same, spring means temporarily engaging the pawls during their downward movement to press their dogging ends into ratchet engaging position, together with catch means 90 engaging the pawls during the pressure of said spring means when said shaft is rotating in one direction, said catch serving to prevent the ratchet engaging movement of the pawls while under the influence of said spring means.

5. A lifting jack comprising a jack bar, a pawl and ratchet mechanism for operating the same, said mechanism comprising a plurality of working pawls, a shaft continuously rotatable in one direction to operate 100 the same, spring means temporarily engaging the pawls during their downward movement to press their dogging ends into ratchet engaging position, together with common 105 catch means engaging the pawls during the pressure of said spring means when said shaft is rotating in one direction, said catch serving to prevent the ratchet-engaging movement of the pawls while under the influence of said spring means.

6. A lifting jack comprising a jack bar, a pawl and ratchet mechanism for operating the same, said mechanism comprising a plurality of single-tooth pawls, a continuously 115 rotatable member for actuating the latter, a spring-pressed lever lying in the path of the free ends of the pawls and temporarily engaging the latter during the non-working travel of the pawls to press the latter into ratchet-engaging position on the rotation of 120 the actuating shaft in one direction.

7. A lifting jack comprising a jack bar, a pawl and ratchet mechanism for operating the same, said mechanism comprising a plurality of single-tooth pawls, a continuously 125 rotatable member for actuating the latter, a spring-pressed lever lying in the path of the free ends of the pawls and temporarily engaging the latter during the non-working travel of the pawls to press the latter into 130

ratchet-engaging position on the rotation of the actuating shaft in one direction, together with a catch on said lever engaging said pawl ends and serving to hold the pawls temporarily out of engagement with the ratchet on the rotation of the shaft in the opposite direction.

In testimony whereof I have signed my name to this specification in the presence of two subscribing witnesses.

RICHARD T. NEWTON.
